UNITED STATES PATENT OFFICE.

ABNER B. CLEMENTS, OF BUTTE, MONTANA.

COMBINATION BANKING-BOOK.

SPECIFICATION forming part of Letters Patent No. 752,520, dated February 16, 1904.

Application filed December 9, 1903. Serial No. 184,420. (No model.)

To all whom it may concern:

Be it known that I, ABNER B. CLEMENTS, a citizen of the United States, residing at Butte, in the county of Silverbow and State of Montana, have invented certain new and useful Improvements in Combination Banking-Books; and I do hereby declare the following to be a full, clear, and exact description of the invention, such as will enable others skilled in the art to which it appertains to make and use the same.

My invention relates to improvements in combination blank-books, and is especially applicable for use with banking institutions having savings accounts of out-of-town customers.

It is well known that savings-banks as a rule generally require that the pass-book of a depositor be surrendered to the bank with each order on the bank or check as drawn, so that entry may be made thereon immediately to give the depositor the balance to his credit. This results in great inconvenience at times to depositors, and the present invention is intended to obviate this objection by the use of an order or check book adapted also to contain receipts for deposits and notice of withdrawals from the bank, thus acting as a combined check and pass book.

To more fully describe my invention and the system to which it is especially applicable, reference is had to the accompanying drawings illustrating the same, in which like letters designate corresponding parts in the several views, and in which—

Figure 1 represents a plan view of the open book, showing the face of a check and the rear face of an entry-slip or stub, the top cover of the book being broken away. Fig. 2 is a similar view showing the back of the check and the front face of the entry-slip or stub, the rear cover being broken away; Fig. 3, a plan view of the open book, showing the rear face of the entry-slip or stub on the left and the front face of the next succeeding one on the right with a deposit-receipt pasted thereon; Fig. 4, a similar view showing the application of the notice of withdrawal or charge-slip;

Fig. 5, a perspective view of a modified form of book using a folded check; Fig. 6, a plan view of another modified form of book illustrated as being open and showing the rear and front faces, respectively, of the entry-slip or stub and a detachable combined order-blank and deposit-slip; Fig. 7, a similar view to Fig. 6, showing the reverse faces of the entry-slip or stub and the detachable slip; and Fig. 8 is a view substantially similar to Fig. 2, a part being broken away, illustrating a still further modified form, showing both the deposit-slip and order-blank on the rear face of the check.

Referring now to Figs. 1 to 4, A represents the check; B, the entry-slip or stub, a plurality of which are alternately arranged in book form within the covers C D. The front face A' of the check is provided with the usual form of order and on the back A² thereof is printed the usual form of deposit, the rear face of the check constituting a deposit-slip if it is desired to make a deposit. Alternating with each check and preferably shorter in length is arranged the stub portion B, the front face B' of which is provided with a printed memorandum substantially to the effect to "Stick acknowledgment of deposit or check corresponding to preceding stub here," and the reverse side B² is provided with the usual form common to check-book stubs.

E represents the bank-receipt or acknowledgment of deposit pasted on the front face B' of the stub, which was located immediately behind the check, which in this case was used as a deposit-slip.

F represents a charge-slip or notice of withdrawal similarly replacing the check, which in this instance has been used to draw on the account, instead of as a deposit-slip. This charge-slip is preferably of a prominent color to avoid confusion, and in the drawings I have illustrated it as being green, although it is manifest that any other suitable color might be used.

In the modification illustrated in Fig. 5 the arrangement is substantially similar to the preceding figures, with the exception that the

book is simply shortened, the check being transversely folded centrally, as at A⁹.

The form shown in Figs. 6 and 7, where the book is intended more particularly for use in dealing directly with the bank without the mediation of a check to third parties, is substantially, in effect, the same as in the previous figures in savings accounts. In this form of book, however, it will be observed that the blank form of check has been dispensed with and a detachable slip inserted in lieu thereof containing on one face, A³, the printed form of deposit and on the reverse face, A⁴, an order-blank form, the use of which avoids the necessity of the customer writing out both a check and a letter of instructions, the blank order-form when filled out serving in this dual capacity.

In the form illustrated in Fig. 8 the arrangements disclosed in the previous figures are combined in a single book, in this figure A⁵ designating the back of a blank check-form, which may be folded, as in Fig. 5, and A⁶ and A, respectively, the blank form of deposit-slip and order-blank printed alongside each other on the back of the check-form. It is obvious, however, that although I have shown these blank printed forms as extending longitudinally of the check-form they may be disposed transversely thereof or one transversely and the other longitudinally thereof, as may be desired.

To illustrate the application and use of my improved combined order or check and pass book, and referring more particularly to Figs. 1 to 4, we will assume that check No. 1 has been filled out as a deposit-slip and, together with one hundred dollars, mailed to the bank. Upon the receipt of the same the bank fills out the slip E, which is mailed to the customer and forms a receipt for the deposit, in place of the usual form of entering a deposit on the ordinary pass-book. This receipt is then pasted by the customer upon the front face B' of the stub which has been exposed by the tearing out of the blank check. We will now assume that check No. 2 has been used to draw on the account for fifty dollars. In this instance when the check has been received and paid by the bank the bank mails to the customer the green notice or charge-slip F, showing the balance to the customer's credit at the bank, this in lieu of necessitating the customer bringing his pass-book with the check to the bank and having the entry of withdrawal made on the pass-book simultaneously with the payment of the check.

With reference to Figs. 6 and 7 the idea is substantially the same, the detachable combined withdrawal order-blank and deposit-slip corresponding, in effect, to the combined blank check-form and deposit-slip.

The use of the book illustrated in Fig. 8 is clear in view of the foregoing, and it will be observed that in any of my forms of book a system can be carried out whereby the objection of handing in the pass-book with each deposit or withdrawal is obviated, making the system especially suitable for business with out-of-town customers.

What I claim is—

1. A blank order-form provided on its reverse face with a blank form of deposit.
2. A banking-book comprising a plurality of blank order-forms provided on their reverse faces with a blank form of deposit, a plurality of entry-slips alternating therewith, and a suitable cover therefor.
3. The combination with a withdrawal order-book comprising a plurality of blank order-forms, a plurality of entry-slips alternating therewith, and a suitable cover therefor, of means coöperating with said order-book for also utilizing the same as a pass-book and maintaining the balance to the customer's credit substantially as each transaction is completed, comprising bank charge and credit slips adapted to be pasted on the front face of said entry-slips in lieu of the used and detached order-form.
4. The combination with a withdrawal order-book comprising a plurality of blank order-forms, provided on their reverse faces with a blank form of deposit, a plurality of entry-slips alternating therewith, and a suitable cover therefor, of means coöperating with said order-book for also utilizing the same as a pass-book and maintaining the balance to the customer's credit substantially as each transaction is completed, comprising bank charge or credit slips adapted to be pasted on the front face of said entry-slips in lieu of the used and detachable order-form or deposit-slip.
5. A blank form of check provided on its rear face with a blank form of deposit.
6. A check book comprising a plurality of check-forms provided on their rear faces with a blank form of deposit, a plurality of entry-slips alternating therewith, and a suitable cover therefor.
7. A check-book comprising a plurality of check-forms provided on their rear faces with a blank form of deposit, a plurality of entry-stubs alternating therewith, and a suitable cover therefor.
8. A blank form of check provided on its rear face with a blank form of deposit and a blank order-form.
9. A check-book comprising a plurality of check-forms provided on their rear faces with a blank form of deposit and a blank order-form, a plurality of entry-slips alternating therewith and a suitable cover therefor.

10. A check-book comprising a plurality of folded check-forms, provided on their rear faces with a blank form of deposit, a plurality of entry-slips alternating therewith, and a suitable cover therefor.

11. A check-book comprising a plurality of check-forms transversely folded substantially centrally thereof and provided on their rear faces with a blank form of deposit and a blank

order-form, a plurality of entry-slips alternating therewith, and a suitable cover therefor.

In testimony whereof I affix my signature in presence of two witnesses.
